UNITED STATES PATENT OFFICE.

ROY H. FINK, OF CHICAGO, ILLINOIS.

HOISTING MACHINE.

Application filed September 19, 1927. Serial No. 220,307.

This invention relates to hoisting machines, and has reference more particularly to hoisting machines of the character employed in building operations for raising building material to the floor or floors of the structure on which it is to be used. One well-known type of hoisting machine of this character employs a single hoisting drum on which the intermediate portion of a cable is wound, the end portions of the cable extending over suitable guide pulleys on the supporting frame work of the cages or buckets and connected to the latter so that as the drum is rotated the loaded bucket or cage is elevated and the empty bucket or cage is simultaneously lowered. Machines of this character effect what is known as counterbalanced operation and manifestly effect a saving of power over two independently operated hoisting machines; but such machines possess a disadvantage in that they can serve only one floor or level of a building at a time. To serve different floors of the building at the same time it has heretofore been necessary to employ two independently operating hoisting machines.

An important object of my present invention has been to provide a hoisting machine capable, through manipulation of a few manually operated controls, of functioning either as a single hoisting machine operating on the counterbalanced principle or as independent machines capable of operating either of two lifts alone, or both at the same time and delivering the load of each at any desired level. In carrying out the invention I employ a pair of drums or reels, in association with mechanism whereby both drums may be geared together to simultaneously rotate in opposite directions so that, with independent cables wound in the same direction thereon, one drum will be hoisting a load while the other is lowering the empty lift, and vice versa, thus producing counterbalanced operation, or both drums may be operated independently to both raise and lower their respective lifts and deliver the loads at any desired level.

My invention, its mode of operation, and the advantages inhering therein will be readily understood by persons skilled in the art as the same becomes better known through reference to the following detailed description, taken in connection with the accompanying drawings wherein I have illustrated a

practical and approved embodiment of the invention, and in which—

Fig. 1 is a top plan view, in partly diagrammatic form;

Fig. 2 is a side elevation, viewed from the bottom of Fig. 1.

Referring to the drawings, 10 designates a foundation or base plate on which are mounted a pair of parallel skeleton side frames 11 and 12. Journaled in suitable bearings on 65 these side frames are parallel drum shafts 13 and 14. Loose on shaft 13 is a cable winding drum 15 and loose on shaft 14 is a similar cable winding drum 16. Power from an electric motor, gas engine or any other power 70 generator conventionally illustrated at 17 is transmitted through a pinion 18, gear 19, cross shaft 20 and pinion 21 to a large gear 22 which is keyed on shaft 13. The drum 15, which is loose on shaft 13 is connected to or 75 disconnected from gear 22 by a manually controlled friction band clutch mechanism indicated at 23, operated by a hand lever 39, with the structural details of which the present invention is not concerned. The friction 80 band clutch mechanism herein indicated is shown and described in Letters Patent to W. A. Barker No. 1,054,666, dated March 4, 1913, to which reference may be had for a description thereof. Fast on the other end 85 of drum 15 is a large gear 24 that is continuously in mesh with a similar gear 25 loose on shaft 14. Gear 22 drives a similar gear 26 fast on shaft 14 through an intermediate gear 27 (Fig. 2), whereby the gears 22 and 90 26 always rotate in the same direction. Drum 16, loose on shaft 14, is connected to and disconnected from gear 26 by a friction band clutch mechanism 23' similar in all respects to the friction band clutch mechanism 95 23, and operated by a hand lever 39'. The gear 25, which runs loose on shaft 14, may be connected to and disconnected from the drum 16 by a sliding clutch 28 mounted on shaft 14 outside the gear 25, said clutch having pins 29 100 extending through holes in the web of gear 25 and adapted to enter holes 30 formed in the head of drum 16; said clutch being operated by a hand lever 32 pivoted at 33 on a bracket 34 mounted on the side frame member 12. When clutch 28 is engaged so as to lock gear 25 to drum 16, it may be locked in such position by a suitable pin passed through mating holes 35 and 36 in the lever 32 and a fixed segment arm 37.

To the other head of each drum is applied a brake band 38, one end of the band being attached at 40 to the frame base 10, and the other end being attached to a short arm 41 fast on a rock-shaft 42 journaled in the frame base. The two rock-shafts 42 are actuated to apply the brakes by pedal levers 43, 43' fast thereon; and each rock-shaft 42 is urged in a direction to release the brake by a torsion spring 44 (Fig. 1), one end of which spring is anchored in a lug 45 on the frame base through which the rock-shaft passes, and the other end of which is anchored in a collar 46 on and adjustable around the rock-shaft 42 to vary the tension of the spring, said collar being secured in adjusted position by a set-screw 47.

Assuming that it is desired to operate two hoists independently through independent cables wound on the respective drums 15 and 16, clutch 28 is disengaged and either or both clutches 23 and 23' are engaged. Engagement of clutch 23 only will operate drum 15 only, and engagement of clutch 23' only will operate drum 16 only. If both clutches 23 and 23' are engaged, both drums will rotate in the same direction, the drive being through gear 22, intermediate gear 27 and gear 26. Thus, when working on different levels, by disengaging clutch 28 and manipulating clutches 23 and 23', the two drums can be started and stopped independently to hoist their respective loads through the same or different distances.

To drive both drums simultaneously in opposite directions, as in counterbalanced work where one cage or bucket is being hoisted while the other is descending, clutch 28 is engaged, which locks gear 25 to drum 16, and then by disengaging either clutch 23 or clutch 23' and engaging the other, the two drums will turn simultaneously in opposite directions. If clutch 23 be engaged and clutch 23' disengaged, then drum 16 is driven from drum 15 through gears 24, 25 and clutch 28. If clutch 23' be engaged and clutch 23 disengaged, then drum 15 is driven from drum 16 through clutch 28 and gears 25, 24. Thus in such counterbalanced operation, drum 15 may run clockwise and drum 16 counterclockwise, to hoist the loaded bucket or cage and lower the empty bucket or cage; and after the loaded bucket or cage has been emptied and the empty bucket or cage has been loaded, the drum 15 may be rotated counterclockwise and the drum 16 clockwise to lower the then empty bucket or cage and hoist the then loaded bucket or cage.

I claim—

1. In a hoisting machine, the combination of a frame, a pair of parallel drum shafts journaled in said frame, winding drums on said shafts, a gear train having clutch connections to both of said drums at one end of

the latter through which said drums may be rotated independently or simultaneously in the same direction, a second gear train having a fixed connection to one of said drums and a clutch connection to the other drum at the other end of said drums through which said drums may be rotated in opposite directions, and means for driving said first-named gear train.

2. In a hoisting machine, the combination of a frame, parallel drum shafts journaled in said frame, winding drums loose on said shafts, a pair of gears on the respective drum shafts, a transmission gear between said gears, independently operable clutch connections between the gears of said pair and the adjacent ends of said drums, intermeshing gears on the respective drum shafts, one of said intermeshing gears being fast with one of said drums and the other having a clutch connection to the other drum, and a driving shaft geared to one of said first-named pair of gears.

3. In a hoisting machine, the combination of a frame, a drum shaft journaled in said frame, a winding drum loose on said shaft, a gear keyed on said shaft opposite one end of said drum, a clutch for connecting said gear to said drum, a second gear fast on the other end of said drum, a second drum shaft journaled in said frame parallel with said first-named drum shaft, a second drum loose on said second drum shaft, a third gear keyed on said second drum shaft, a clutch for connecting said third gear to said second drum, an idler gear between said first-named gear and said third gear, a fourth gear loose on said second drum shaft intermeshing with said second gear, a clutch for connecting said fourth gear to said second drum, and means for driving said first-named gear.

4. In a hoisting machine, the combination of a frame, a drum shaft journaled in said frame, a winding drum loose on said shaft, a gear keyed on said shaft opposite one end of said drum, a clutch for connecting said gear to said drum, a second gear fast on the other end of said drum, a second drum shaft journaled in said frame parallel with said first-named drum shaft, a second drum loose on said second drum shaft, a third gear keyed on said second drum shaft, a clutch for connecting said third gear to said second drum, an idler gear between said first-named gear and said third gear, a fourth gear loose on said second drum shaft intermeshing with said second gear, a locking clutch slidable on said second drum shaft adapted to couple said fourth gear to said second drum, means for driving said first-named gear, and a pair of independently operable brakes for the respective winding drums.

ROY H. FINK.
